UNITED STATES PATENT OFFICE.

J. RABBETH, OF EAST HARTFORD, CONNECTICUT.

DIAPER-PIN.

Specification of Letters Patent No. 11,272, dated July 11, 1854.

To all whom it may concern:

Be it known that I, J. RABBETH, of East Hartford, in the county of Hartford and State of Connecticut, have invented a new 5 and useful Improvement in the Victoria Diaper-Lock; and I do hereby declare that the following is a full, clear, and exact description of the same, reference being had to the accompanying drawing, forming part of 10 this specification, in which—

Figure 1, is an inverted plan of the diaper lock, as it appears when locked. Fig. 2, is a side view of the same, not inverted. Fig. 3, is a vertical longitudinal section of the 15 same, as it appears when unlocked. Fig. 4, is a horizontal section of the pin inverted. Fig. 5, is a vertical transverse section of the diaper lock through the line, α , α , in Fig. 1. In this view it is shown locked. Fig. 6, is a 20 vertical transverse section of Fig. 2, through the line, y , y . In this view the diaper lock is shown unlocked. Fig. 7, is a vertical transverse section of Fig. 1, through x , x , on a greatly enlarged scale. Fig. 8, is a side 25 view of the diaper pin, patented by Woodward, in May, 1842. Fig. 9, is a transverse section of the same through the protective loop. This pin is represented for the purpose of showing plainly the difference existing between it and my diaper lock. 30

Similar letters of reference in each of the several figures indicate corresponding parts.

This invention relates to an improvement in the diaper lock patented by Woodward 35 in May, 1842, whereby all liability of the pin getting out of its place, and pricking the child, is avoided. In the Woodward lock, the pin is only kept confined so long as the child lies still, and in one position, or while 40 sufficient pressure is brought to bear against the pin, to keep it rigidly against the protection loop; which cannot always be the case. In my lock, this is not necessary.

The nature of my invention consists in 45 arranging a slotted tube permanently on one end of the pin holder, and inserting in said tube another slotted tube, which is capable of revolving. The slots in the tubes serving to allow the point of the pin to pass 50 into the inner tube, and the inner tube serves to securely confine the point of the pin after the diaper has been properly secured. The slots in the tubes being in line with each other when the point of the pin is 55 passed into the inner tube, and out of line with one another when the point of the pin is locked in its place.

To enable others to understand more

clearly, my invention, I will proceed to describe it more minutely.

A, in the accompanying drawing represents the pinholder, having its two ends, a , b , bent at right angles, A. B, is the pin attached loosely to one of said ends. C, is the outer tube attached fast to the other end, b , of the pin-holder, A. This tube is open at both ends, and has a slot, c , cut in it, along its whole length, as shown in Figs. 1, 3, and 7. This slot allows the pin to pass into the inner tube, D, when it is in line with the slot, d , of the tube, D. The journal, f , of the tube, D, passes through the end, b , of the pin holder; the tube fits loosely in the outer tube, C, and turns freely in the same—its slot being brought in line with the slot, c , of the tube, C, when it is desired to pass the point of the pin into the tube, D, and moved out of line after the point of the pin has been passed into the tube, when it is desired to lock the pin securely in the tube, D.

E, is a thumb head secured on the end of the tube, D. By this head, the tube is turned, and prevented from moving longitudinally, or getting out of place.

By examining Fig. 5, the manner in which 85 the slots come in line with one another, when it is desired to lock the point of the pin in the tube, D, will be clearly seen; and by examining Fig. 7, the manner in which the slot, d , is moved out of line with that, c , 90 and the pin locked securely in the tube, will also be seen.

The pin or diaper lock shown in Fig. 8, has a loop, g , on one of its ends, and two side slots, h , h ; through either of which the pin 95 is passed, and can escape, and prick the child.

I do not claim a diaper lock having a loop which is concave, formed on one of its ends for the pin to be retained under, and 100 two side slots, between said loop and the pin holder for the pin to pass through, as such a pin was patented by Woodward, in May 1842, but

What I claim as my invention, and desire 105 to secure by Letters Patent, is—

The combination of the slotted permanently fixed tube, C, with the revolving slotted tube, D, arranged and operating in the manner, and for the purpose set forth 110 and specified.

J. RABBETH.
